(57) **CLAIM**

The ornamental design for a shower curtain rod assembly, substantially as shown and described.

DESCRIPTION

FIG. 1 is a plan view showing the top of the preferred embodiment of my invention as it would appear mounted within a shower enclosure;

FIG. 2 is a plan view showing the bottom of the preferred embodiment of my invention;

FIG. 3 is a elevational view showing the front of the preferred embodiment of my invention;

FIG. 4 is a elevational view showing the back of the preferred embodiment of my invention;

FIG. 5 is a elevational view showing one side of the preferred embodiment of my invention, the other side being the mirror image of the side shown; and,

FIG. 6 is a partial, enlarged isometric view of the area circled and labeled 6 in the FIG. 1 view.

The broken line and dashed and dotted line borders and environmental structure shown in the FIGS. 1 and 6 views are for illustrative purposes only and form no part of the claimed design.
